COMMUNICATION SYSTEM

Harold J. McCreary, Lombard, Ill.

Application October 19, 1939, Serial No. 300,219

15 Claims.

(CL. 179—1)

The invention relates generally to communication systems, and more particularly to such systems of the two-way, loud-speaking type wherein each station comprises both a microphone and a loud speaker, and wherein speech impressed on the microphone of either station is reproduced at a comparatively high level or intensity by the loud speaker of the other of the station.

With conventional systems of this general character, it is well known that there is often an objectionable feed-back of the high level reproduced sound through the microphone of the "receiving" station. Such objectionable feed-back takes place principally at the higher levels of sound intensity, and the magnitude of the feed-back may vary considerably with many factors of installation and design. However, as a general observation, it may be said that the feed-back for any particular installation becomes distinctly objectionable when the amplification factor exceeds a particular value which may for present purposes be termed the "howl level" or "howl threshold."

Because of this objectionable characteristic in systems of this character, it is often found necessary to abandon the desired automatic or constant connection characteristics of the systems, and to interpose a two-way manual control switch whereby the user may connect the channels for either speaking or listening. Such systems with their manual control key may be termed "manual" or "non-automatic" systems, while the constantly connected systems may for present purposes be termed "automatic" systems.

Since the feed-back of the reproduced sound creates objectionable and undesired noise and audible interference, and often results in unintelligibility of the desired spoken message, it is an important object of the present invention to prevent such objectionable feed-back and the resulting noise and unintelligibility which normally occurs in automatic systems of this character.

A further and more specific object of the present invention is to provide an automatic or constantly connected two-way, loud speaking communication system wherein a vocal or other sound wave impressed upon and reproduced by either one of the communication channels is ineffective to produce objectionable feed-back of such sound along the other of the channels, whereby to prevent the objectionable sound interference and noise above discussed.

A further object of the present invention is to provide such an automatic system wherein the sound transmitted and reproduced through the

agency of either of the two communication channels provides and serves as a controlling force acting to suppress objectionable feed-back of such reproduced sound in the other of the channels.

A further object of the invention is to provide such an automatic or constantly connected two-way loud-speaking communication system wherein a relatively low normal gain in both communication channels is automatically varied by sound-induced currents in either one of the channels to decrease the normal gain in the other or return channel and to increase the normal gain in the first or primary channel; and it is a further and related object of the invention to produce such a system wherein sensitivity and responsiveness as to such voice-induced variation is facilitated through the use of a relatively high voltage voice-induced control current in combination with automatic means operable to limit the voice-induced variation in gain in either or both of the channels.

A further object is to provide such a two-way constantly connected communication system wherein the microphone means and the reproducing means at each station are so arranged and related in an acoustic sense that the sounds of the predominating frequency of the system reproduced after transmission through one of the channels are, in effect, cancelled out in the return channel, and are thereby rendered ineffective to actuate the loud speaker at the original source of the sound, this objective being attained by means which is ineffective to cancel out the predominating frequency in the primary channel.

A further object is to provide such a two-way system wherein acoustic means for reducing the effective feed-back is combined with automatic voice-induced reduction of the amplification factor in the return channel.

Other objects and advantages will become apparent from the following description, taken in connection with the accompanying drawings, in which:

Fig. 1 is a diagrammatic illustration of a communication system embodying the invention.

Figs. 2, 2a and 2b are diagrammatic illustrations of alternative forms of the invention wherein feed-back is reduced by acoustic treatment.

Fig. 3 is a diagrammatic illustration of a second alternative embodiment of the invention wherein the desired result is attained through a combination of acoustic and electrical means.

Fig. 4 is a wiring diagram showing the circuits employed in the embodiment of Fig. 1.

In the form chosen for disclosure in Figs. 1 and 4 of the drawings, the invention is embodied in an automatic two-way loud-speaking communication system having two similar terminal stations or sets 10a and 10b which in practice are located remote from each other, as in separate rooms 11 and 12. Each terminal set comprises a microphone 14 and a loudspeaker 15, these elements of the two units or sets being distinguished by the use of the letters a and b in accordance with the set to which they belong. Thus the microphone 14a and the loudspeaker 15a form the elements of the set 10a, and may be mounted in a suitable cabinet 16a, indicated in dotted outline in Fig. 4, while the corresponding elements of the set 10b may be mounted in a similar cabinet 16b.

The two sets 10a and 10b are interconnected through amplifying and control means which in Fig. 1 is indicated generally by the reference numeral 20, there being a first transmission path or channel 21 between the microphone 14a and the loud speaker 15b, and a second transmission path or channel 22 between the microphone 14b and the loud speaker 15a.

In a conventional automatic system of the general character above described, where both transmission paths, as the paths 21 and 22, are normally open or conditioned for the transmission of sound, a sound impressed upon the microphone 14a would be reproduced by the associated loud speaker 15b at a comparatively high level of intensity, so that the reproduced and amplified sound would be impressed upon the microphone 14b and fed back along the channel 22 so as to be amplified by the loud speaker 15a in the room in which the sound originated. Thus objectionable oscillation or "howl" would be set up in the system.

This objectionable tendency is, for all practical purposes, eliminated by the present invention through the provision of means whereby the energy of the sound originally impressed upon either one of the two channels 21 or 22 acts to prevent objectionable feed-back along the other one of the circuits. I have in the drawings illustrated two different means operable to accomplish this desired suppression of feed-back, and these two means may be employed singly or in combination with each other as will hereinafter be pointed out.

In the form disclosed in Figs. 1 and 4 of the drawings the objectionable feed-back is prevented through electronic means which is automatically actuated and controlled by sound or voice energy impressed upon either one of the transmission channels 21 or 22 to reduce the transmission effectiveness of the other of the paths. Since each of the paths 21 and 22 normally includes amplifier means, such reduction in the transmission effectiveness of the return path is attained through reduction in the amplification factor of the amplifying means of the return transmission path.

65 The transmission channels generally

In the form of amplifying means 20 which is shown in detail in Fig. 4 of the drawings, each channel includes two stages of amplification, and the channels are generally similar in structure and operation, and hence for purposes of disclosure, only the elements of the channel 21 will be described in detail herein. The microphone 14a has a circuit 23 connected thereto including a power source such as a 1.5 volt dry cell 23', and

also including the primary 24' of an input coupling transformer 24 whereby the microphone is connected to the amplifying means. The secondary 24" of the transformer 24 is shunted by an input control potentiometer 25, preferably of about 250,000 ohms, the adjustable contact 25' of which is connected by a lead 26 to the input grid 29 of a first amplifier tube 28. The tube 28 may be of the type and construction identified commercially as the type 6J7. The other or zero end 10 of the potentiometer 25 is grounded at 29' by a lead 30, and from the lead 30 a wire 31 extends to the cathode resistor 32 which is in turn connected to the cathode 33 of the tube 28. The resistor 32 may be in the order of 600 ohms, and is shunted by a by-pass condenser 34 of 5. microfarads.

The plate-cathode circuit of the tube 28 is formed by a lead 35 from the plate 36 of the tube, a plate resistor 37 of about 100,000 ohms, a condenser 38 of about 16 microfarads, preferably electrolytic in character, and a lead 39, all connected in series to the juncture of the wire 31 and the resistor 32. The normal gain of the tube 28 is determined to some extent by the positive bias on a control grid 29" of the tube 28, this normal bias being applied by direct connection of the grid 29" to the cathode 33 of the tube 28. From the juncture of lead 35 and resistor 37, a lead 40, a coupling condenser 41 of .05 microfarad, and a lead 42, all in series, are connected to the control grid 43 of a second amplifier tube 44. The tube 44 is preferably the tube known commercially as type 25L6. From the lead 42 a grid resistor 45 of 500,000 ohms is connected in series with a wire 46 to the lower end of a cathode resistor 47 of 300 ohms, this lower end of resistor being grounded at 29', while the upper end is connected to cathode 48 of the tube 44. The cathode resistor 47 is shunted by an electrolytic condenser 49 of 10 microfarads.

The other grid 50 of the tube 44 is connected to one end of the coil 51 of an output transformer 52 by means of a wire 53, while the plate 54 of the tube 44 is connected by a wire 55 to another point along the coil 51. The speaker 15b is coupled to the coil 51 by a secondary 56, opposite ends of which are connected to the terminals of the speaker. Preferably both the microphone circuit 23 and the secondary 56 of the speaker coupling are grounded to the frames of their respective cabinets as at 57. The ground 57, and all grounds shown in dotted lines, are also connected to earth so as to constitute true ground connections. The other grounds such as 184, 19', 55, 84a and 102a, indicated by solid lines, are true grounds so far as audio frequency is concerned, but are not connected to earth except through condensers. This arrangement reduces danger due to shocks, and assists in reducing hum.

As hereinbefore pointed out, the other channel 22 is of the same construction and arrangement as the channel 21, which has been described in detail, and for purposes of simplicity, corresponding reference numerals are applied to such corresponding elements of channel 22 as require designation or discussion, with such reference numerals prefixed in each instance by the numeral "2". Thus the first amplifier tube of the channel 22, which corresponds with the tube 28, is designated 2-28; the second tube is designated 2-44; while many of the corresponding elements of the channel 22 are not specifically numbered by reason of the fact that they do not 75

require specific consideration in succeeding portions of this disclosure.

In the illustration of Fig. 4, the heater circuits have for purposes of simplicity, been eliminated.

5

The power supply

As a power supply for the system of Fig. 4 I have illustrated a conventional A. C.-D. C. power supply unit 180 adapted for connection by an attachment plug 181 to any 110 volt line, and having terminals 182 and 183 to which the various tubes are connected. It will be noted that one point of negative potential in the unit 180 is grounded at 184 so as to provide a source for the 15 several grounded cathodes of the system.

The sound governed control means

To attain the desired reduction in the amplification factor of the second or return channel, 20 the present invention utilizes the energy of the sound impressed on the first or desired channel, this control energy being applied through suitable intermediate means to the third control grid 60 of the tube 28 of the return channel.

As an additional operational feature, the present invention also provides for automatically increasing the gain or amplification factor of the initial or desired channel simultaneously with the reduction in gain in the return channel. 30 Moreover, the present invention provides for limiting such automatic variation in the amplification factor of the two channels, whereby the system may be rendered highly sensitive to speech impressed on either channel without involving undue variation in gain or volume during the actual conversation over the two channels.

Thus a voice induced control potential or current is taken by a wire 61 from the upwardly 40 extended end 62 of the primary coil of the speaker coupling, this connection being in the nature of an auto transformer which impresses a relatively high potential on the wire 61. From the wire 61 the control current, which is pulsating direct current, is applied to branch leads 64 and 45 65 to a pair of similar control tubes 66 and 2-66, each branch lead 64 and 65 having a condenser 67 therein, of about .005 microfarad, which act to allow only the alternating components of the 50 control current to pass to the control tubes 66 and 2-66.

Considered generally, the two tubes 66 and 2-66 are energized by the alternating components of the control current from the wire 61 of the channel 21 so as to apply a positive potential to the grid 60 of the channel 21, thereby to increase the normal gain of the channel 21, and also to apply a negative potential to the grid 2-60 of the channel 22, thereby to reduce the 55 normal gain in the channel; it being understood, of course, that this action is reversed in the event that the voice energy is initially applied to the channel 22.

To attain this desired functioning for both 60 channels, each control tube 66 and 2-66 is preferably in the form of a duo-diode (herein disclosed as a 6H6 tube), and the mode of connecting these tubes will be described in detail as applied to the channel 21. Thus the tube 66 has 70 one plate 69 connected to wire 65 which carries the control current from channel 21, while its other plate 70 is connected to the wire 2-61 which carries the control current from the channel 22. One cathode 71 of the tube 66 (the cathode opposite the plate 70) is connected through

a potentiometer 72 of 100,000 ohms to ground at 74a. The potentiometer 72 is shunted by a bypass condenser 72' of 10 microfarads, so that the cathode 71, so far as alternating current is concerned, is at ground potential. The other cathode 71' of the tube 66 is similarly at ground potential as to A. C. currents, in view of the circuits which will hereinafter be described. Since one end of the potentiometer 72 is grounded it will be seen that the adjustment of the potentiometer will produce a predetermined adjustable positive potential which is applied through wires 81 and 84, resistor 83, wire 85, resistor 76, choke 77 and wires 78 and 79 to the grid 60 so as to determine the gain of the tube 28 during 15 periods of inactivity or non-use of the channel 21. As to the tube 66, it will be evident that both diodes are inactive until the plates of the tube are rendered more positive than the cathodes 71 or 71' by the application of alternating 20 currents to the plates thereof, and that either of these diodes may be rendered conductive independently of the other.

The plate 69 of tube 28 has a constant predetermined positive potential applied thereto 25 through the plate resistor 37, the remote or lower end of which is connected through a filter choke 30' of 30 henrys, and wires 190, 191, 192, and 193 in series to the terminal 183 of the power supply. From the lower end of the plate resistor 37 a filter condenser 38 of 16 microfarads is connected by means including wires 39 and 31 to ground at 29'. From the juncture of wires 190 and 191 a wire 194 extends to the end of the potentiometer 72. Similarly a wire 195 extends from the juncture of wires 191 and 192 to the lower end of the coil 51.

Thus when the plate 69 is rendered more positive than the cathode 71' by the application of alternating current to plate 69, negative electrons gather on the plate 69, and this flow is utilized to produce a relatively constant potential to be employed in increasing the gain in the tube 28. Thus, a resistor 75 of 100,000 ohms is connected to wire 65, a resistor 76 of 250,000 ohms is connected to the other end of resistor 75, and the other end of resistor 76 is connected by a wire 71" to the cathode 71' of the tube 66. Around the resistor 76 a condenser 76' of .25 microfarad is shunted. From the lower end of the resistor 76, that is the end which is connected to cathode 71', an audio choke 77 of 30 henrys is connected to a wire 78, which wire is connected to a wire 79 which extends to the grid 60 of the tube 28. A condenser 80 of .05 microfarad is 55 connected between the juncture of resistors 75 and 76 and the juncture of wires 78 and 79. With this structure a flow of electrons to plate 69 establishes a relatively steady positive potential at the choke 77 which acts to increase the 60 gain in the tube 28. This positive potential varies, of course, with the intensity of the voice-induced control current in the wire 61, and actually tends to reach an exceedingly high level which would produce an undue and undesired 65 objectionably large increase in the gain of the tube 28, and as will hereinafter be pointed out, the present invention provides for limiting the amount of gain which can be induced in the channel by this variable positive potential.

Considering the opposite channel as being the source of the voice-induced control current, as when a sound is impressed on the channel 22, the control current corresponding to that above discussed, would be on the wire 2-64, and the 75

control potential impressed on the grid 60 of the channel 21 would be negative rather than positive, and the gain in the channel 21 would be reduced. To accomplish this result, the plate-cathode circuit of the plate 70 and cathode 71 has a resistance-capacitance filter system generally similar to the other diode of the tube 66. Thus a resistor 82 of 100,000 ohms has one end connected to wire 2-64, a second resistance 83 of 250,000 ohms being connected in series with the other end of resistor 82 to a wire 84 which is connected to the cathode 71. A capacitance of 10 microfarads is connected between the wire 84 and ground at 84a; while a capacitance 82' of .1 microfarad is shunted around the resistor 83. From the juncture of resistors 82 and 83 a conductor strap 85 extends to the juncture of resistors 75 and 76.

Thus when the diode 71-70 is rendered conductive by a voice-induced alternating control current in wire 2-64, the resistance capacitance filter system associated with plate 70 establishes a relatively constant negative potential at the juncture of strap 85, with the filter system of the plate 70, and this negative potential is applied through the strap 85 and the other (and now inactive) filter system so that a negative potential is applied through the choke 77 and wires 78 and 79 to the grid 60.

30 *The limiting means for the sound governed control*

As hereinbefore mentioned, the present invention contemplates the use of control currents which are of a relatively high voltage as compared with level of the sound which produces such control currents, thus insuring sensitivity and prompt response when a sound is impressed on one of the channels. This use of high voltage control currents is made possible, in accordance with the present invention, through the provision of means for limiting the voice-induced increase in gain which is introduced into the primary channel, and for limiting the voice-induced reduction in gain which is produced in the other or return channel. This end is attained through a control tube 100 which acts to limit the increase in gain in either of the channels, and through a control tube 101 which acts to limit the reduction in gain in either of the channels. These tubes 100 and 101 may be of the 6H6 type as herein shown.

In the circuit herein shown, the tube 100 has both of its cathodes 102 connected to ground at 102a through a potentiometer 103 of 100,000 ohms which is shunted by a by-pass condenser 104 of 10 microfarads. The other end of the potentiometer 103 is connected by a wire 196 to the juncture of wires 192 and 193. Thus the cathodes 102 are connected to the power unit 180, so that an adjustable constant positive potential may be placed on the cathodes. The plate 105 of the tube 100 is connected by wires 106 and 106' to the juncture of the choke 77 and wire 78, so that the plate 105 is charged with the same potential as the grid 60. When this potential is positive and exceeds the threshold value established by the adjustment of the positive potential on cathode 102, the diode 102-105 becomes conductive; and current is drawn so as to reduce the positive potential at the choke 77 to a point where the diode 102-105 becomes or tends to become non-conductive. Hence the voice-induced increase in gain in the tube 28 cannot

exceed a predetermined value determined by the threshold adjustment of the limiting tube 100.

A similar limiting action of the tube 100 on the voice-induced increase in gain in the tube 2-28 is attained by connecting the second plate 5 105' of the tube 100 to the grid 2-60 by wires 107 and 108.

The other control or limit tube 101 serves to limit the voice-induced decrease in gain which is introduced into either of the channels, and to this end the plates 110 and 110' of the tube 101 are connected in parallel by wires 111 and 111' to a constant source of negative potential such as the terminal 182 in the power unit 180. This connection establishes an operational threshold 15 for the tube 101, and if desired, suitable means may be introduced in the lead 111 for variably adjusting the negative potential on the plates 110 and 110'. One cathode 112 of the tube 101 is connected by a wire 113 to wire 108 which leads 20 to the grid 2-60 of the tube 2-28, while the other cathode 112' is connected by a wire 114 to wire 106 which leads to the grid 60 of the tube 28.

Thus when the voice induced negative charge on the grid 2-60 exceeds the threshold-establishing 25 negative potential on plate 110, the diode 110-112 is rendered conductive; and the resulting current flow in effect reduces the negative charge on grid 2-60 until the diode 110-112 is again non-conductive. This action is for all practical purposes instantaneous, so that the gain in the tube 2-28 is never perceptibly reduced beyond the desired minimum.

The other diode 110'-112' of the tube 101 acts similarly to limit the voice-induced reduction in 35 gain in the channel 21.

Operation of Figure 4

Summarizing the operation of the sound system of Fig. 4, the inter-related action of the various 40 tubes and circuits will now be described for each direction of transmission. It will be understood, of course, that the system is ordinarily adjusted as to sensitivity, as by the potentiometer 72, so that the various control elements will be insensitive or unresponsive to ordinary room noises. 45

When a user speaks into the microphone 14a of channel 21, the pulsating voice-induced currents in the coupling 24 are impressed on grid 29 of the tube 28, and are amplified at the normal ratio in the plate circuit of the tube. The amplified potential on plate 36 of tube 28 is impressed on the control grid 43 of the second amplifier tube 44. The plate circuit of tube 44 carries the amplified voice-induced energy and energizes the coupling primary 51 which through its auto-transformer action supplies the requisite pulsating control current of high voltage in the wire 61. For practical purposes this creation of the desired high voltage control current is instantaneous, since it takes place in a time interval so short as to be imperceptible to the human ear. This result is attained by making the time constant of the resistance capacity filter systems very small.

The alternating current components of pulsating control current serve to provide the primary governing force for the desired increase in gain in the primary channel 21 as well as for the desired decrease or reduction in gain in the secondary or return channel 22. In attaining this purpose, the alternating components of the control current from the wire 61 acts upon the diode 69-71' of the tube 66 to provide in its associated filter system the requisite positive potential upon 76

the grid 60 of the channel 21, while the current from the wire 61 acts through the diode 2-69-2-71 of the tube 2-66 and the associated filter system to provide the requisite negative potential upon the grid 2-60 of the tube 2-28.

When the increase in gain thus induced in the tube 28 tends to exceed the predetermined maximum determined by the threshold adjustment of the tube 100, the positive potential of the grid 10 acts on the diode 105-102 of the tube 100 to render said diode conductive, thereby connecting the grid 60 to a source of less positive voltage which, in effect, offsets the undesired excess of positive voltage which has been applied to the grid 60. As a practical matter the maximum positive charge on the grid 60 is limited by the threshold adjustment of the tube 100.

Similarly the negative or gain reducing charge on the grid 2-60 of the return channel 22 is limited by the diode being rendered conductive when the negative potential on the grid 2-60 exceeds or becomes more negative than the threshold-establishing negative potential on the plate 110 of the tube 101.

When a user speaks into the microphone 14b of channel 22, the voice induced currents in the coupling 2-24 are impressed on grid 2-29 of the tube 2-28, and are amplified at the normal ratio in the plate circuit of the tube. The amplified potential on plate of tube 2-28 is impressed on the control grid 2-43 of the second amplifier tube 2-44. The plate circuit of tube 2-44 carries the amplified voice induced energy and energizes the coupling primary 2-51 which through its auto-transformer action supplies the requisite pulsating control current of high voltage in the wire 2-61.

This pulsating control current serves to provide the primary governing force for the desired increase in gain in the primary channel 22 and for the desired decrease in gain in the secondary or return channel 21. In attaining this purpose, the control current from the wire 2-61 acts upon the diode 2-70-2-71 of the tube 2-66 to provide in its associated filter system the requisite positive potential upon the grid 2-60 of the channel 22, while the current from the wire 2-61 acts through the diode 70-71 of the tube 66 and the associated filter system to provide the requisite negative potential upon the grid 60 of the tube 28.

When the increase in gain thus induced in the tube 2-28 tends to exceed a predetermined maximum determined by the threshold adjustment of the tube 100, the positive potential of the grid 2-60 acts on the diode 105'-102 of the tube 100 to render said diode conductive, thereby connecting the grid 2-60 to a source of less positive voltage which offsets the undesired excess of positive voltage which has been applied to the grid 2-60. The maximum positive charge on the grid 2-60 is thereby limited by the threshold adjustment of the tube 100.

Similarly the negative or gain reducing charge on the grid 60 of the return channel 21 is limited by the diode 110'-112' of the tube 101, this diode being rendered conductive when the negative potential on the grid 60 exceeds or becomes more negative than the threshold-establishing negative potential on the plate 110' of the tube 101.

The acoustic system

In Figs. 2, 2a and 2b of the drawings I have illustrated another means for reducing the effective feed back of sound along the return path of

a two-way automatic loud speaking communication system. This means of attaining the desired end may be termed an "acoustic" system, since it is based upon the discovery that the predominant or natural frequency of the reproduced sound of the loud-speaker may be impressed upon the return channel in such a manner as to be rendered ineffective as sound reproducing energy in such return channel. This end is attained by impressing such sound upon the microphone

means of the return channel in two components which are substantially 180° out of phase with each other. One means for attaining this out-of-phase input of the predominating frequency is shown in Fig. 2, wherein two microphones 140a are mounted at a distance apart which is equal to one-half the wave length of the natural or predominating frequency of the system. These two microphones 140a are arranged in the plane of the loudspeaker 150a, so that sound of the predominating frequency will reach the two microphones 140a in a phase displacement of 180°. Thus the electrical impulses produced from the two microphones 140a may be cancelled out by impressing them upon the same channel. In Fig.

2 this operation is illustrated by diagrammatically showing the sounds of the predominating frequency as circles of alternate compressions and rarifications of the air, the rarifications being represented by dotted arcs, and the compressions being represented by dash line arcs. Thus the microphones 140a are connected in series between a wire 151 and a wire 152, the wire 152 having a source of direct current such as a battery 153 therein. The wires 151 and 152 may be considered as a channel 21' which includes an amplifier 155 of conventional construction, the wires 151 and 152 being connected to the loudspeaker 150b of the other station or set. The other channel 22' has two microphones 140b, mounted in the same manner as the microphones 140a, and connected in series between the wire 152 and another wire 154. The wires 152 and 154 therefore form the channel 22', which channel also includes the amplifier 155.

In attaining the desired out-of-phase application of the reproduced sound to the two microphones, I prefer to place the two microphones in a plane which includes the adjacent speaker, as shown in Fig. 2.

A similar cancelling out of the predominating frequency in the return path may be attained by the use of two loud speakers and a single microphone in each of the two sets as shown in Fig. 2a, the two speakers 170 of each set being spaced apart and related to the microphone 171, in the same manner as disclosed in Fig. 2; in other words, the two speakers 170 are spaced apart a distance equal to one-half wave length of the predominating frequency of the system, and are located in the same plane as the microphone 171.

Another mode of attaining this cancelling-out action is shown in Fig. 2b wherein a suitable plane sounding board 173 is positioned so that it reflects the sound to the single microphone 174 in the desired 180° phase relation to the sound reaching the microphone 174 by a direct path.

With the structure of Fig. 2, it will be apparent that the two microphones 140 are ineffective to cause cancelling out of the desired sound, for it will be seen that sound emanating as indicated from a source in front of the set, as from point 160, will reach the two microphones substantially in normal phase relation.

The combined acoustic and electronic system

In Fig. 3 of the drawings I have illustrated an embodiment of the invention wherein the novel amplifying and control unit 20 of Figs. 1 and 4 is combined with the acoustic system of Fig. 2. Thus each set 16' of the Fig. 3 embodies two microphones 140 connected in parallel and spaced and arranged in the same manner as in Fig. 2. The two associated microphones 140 of each set 16' are operatively associated with their communication channel in substantially the same manner as has been described with relation to Fig. 4. Similarly, the system of Fig. 4 may be combined with the acoustic arrangements of Figs. 2a and 2b.

Thus an automatic reduction in gain in the return channel is attained with the same general effect as in the Fig. 4 embodiment, and in addition, the out-of-phase application of the sound of predominating frequency to the return channel further reduces any tendency to produce oscillation in the system. Hence the combined system of Fig. 3 is highly flexible and can be adapted to a wide variety of installation requirements.

Summary

From the foregoing description it will be evident that the present invention prevents objectionable feed-back of sound in a two-way loud speaking communication system, thereby to prevent "howl" or oscillation in the system, and permitting the use of higher levels of transmission than have heretofore been practical. Moreover, the automatic and predetermined increase in gain which takes place in the primary channel enables the user to so adjust the system as to be insensitive to normal room noises; and yet the user may speak into one of the transmitters at close range and instantly establish an increased gain in the system which will transmit the desired message at a readily intelligible level. Since the normal gain in the channels may be adjusted to a point sufficiently low to render the system insensitive to room noises, and the automatically attained operational level of gain may be adjusted to suit installation conditions, it will be evident that the system of the present invention is extremely flexible and adaptable.

This adaptability is founded in a large measure upon the reduction in gain which the present invention introduces in the return channel as an incident to the transmission of sound in the first or primary channel. Since this reduction in gain may be made relatively great so as to reduce the gain to a relatively low level, which may in some instances practically block the return path, it will be evident that the adjustment of the operational level of the primary channel is unhampered and unrestricted by the heretofore important possibility of feed-back and oscillation.

Furthermore, the limiting means which the present invention provides in association with the sound-induced control renders the system highly sensitive and practically instantaneous in response, since it enables the user to make the voice-induced control sensitive to sound only slightly above the normal room sound level, and yet with this great sensitivity the louder sounds of desired conversation are reproduced at a substantially normal level at the reproducer.

With the acoustic system herein disclosed a satisfactory suppression of feed-back and oscillation is obtained in many instances without un-

due cost or modification of existing equipment; and when this acoustic treatment is combined with the electronic system of the present invention, the resulting structure is one which will meet even a wider variation of requirements in installation or use.

I claim as my invention:

1. A communication system comprising means providing two normally active telephonic communication channels each having an input transmitter and loud speaking reproducer, the transmitter of each channel being located adjacent to the loud speaking reproducer of the other channel, and means operable by a relatively low intensity of sound energy impressed on one of said channels to reduce the transmission efficiency of the other of the channels and simultaneously to increase the transmission efficiency of said one of the channels.

2. A communication system comprising means providing two normally active telephonic communication channels each having an input transmitter and loud speaking reproducer, the transmitter of each channel being located adjacent to the loud speaking reproducer of the other channel, each of said channels including variable amplifying means of the electronic type, means operable by relatively low level sound energy in one of said channels to produce a control potential variable between zero potential and a predetermined maximum while the sound impressed on said one channel varies within relatively low range of intensity and maintained at said predetermined maximum while said impressed sound is above said range, and means for applying said control potential to the amplifying means of one of said channels to vary the amplification factor thereof.

3. A communication system comprising means providing two normally active telephonic communication channels each having an input transmitter and loud speaking reproducer, the transmitter of each channel being located adjacent to the loud speaking reproducer of the other channel, each of said channels including variable amplifying means of the electronic type, means operable by relatively low level sound energy in one of said channels to produce a control potential variable between zero potential and a predetermined maximum while the sound impressed on said one channel varies within relatively low range of intensity and maintained at said predetermined maximum while said impressed sound is above said range, and means for applying said control potential to the amplifying means of the other one of said channels to vary the amplification factor in said other channel.

4. In a communication system having means providing two normally active telephonic communication paths each having an input transmitter and a loud speaking reproducer, the transmitter of each channel being located adjacent to the loud speaking reproducer of the other channel, and each channel including grid controlled variable gain amplifying means, a conductor connected to a first one of said channels at a point carrying pulsating direct current when voice energy is being transmitted along said first channel, a thermionic valve operatively associated with said conductor by means including a capacitor to render said valve conductive when the alternating currents of a pulsating direct current on said conductor are applied through said capacitor to said valve, a resistance-capacity filter operatively connected to the plate-cathode cir-

cuit of said valve, a conductor connecting said grid of said amplifying means to said resistance-capacity filter, and a thermionic limiting valve having one of its elements connected to said grid and its other element normally biased at such a potential as to render said limiting valve conductive when the bias on said grid reaches a predetermined value.

5. A two-way communication system of the character described comprising a pair of communication channels each including amplifying means adapted normally to amplify at a relatively low ratio and including a control grid for varying said ratio, means operatively connected 10 to one of said channels and controlled by voice induced currents in said one channel to develop a relatively high control potential, and means for applying said control potential to the grid of one of said amplifying means to vary said normal 15 amplification ratio, said last mentioned means being operable to limit said potential to a predetermined value.

6. In a two-way loud speaking communication system having two channels of communication 25 and an individual amplifier for each of said channels, the combination of control means for said amplifiers operable by sound energy in either channel to introduce a predetermined reduction in the amplification factor of said amplifier of 30 the other or return channel, and to introduce a predetermined increase in the amplification of the channel in which said sound energy was first impressed.

7. In an electrical control circuit, the combination of a diode, an energizing lead for applying alternating current to render said diode conductive, a resistance capacity filter system in circuit with said diode, a useful voltage tap on said filter system for taking off a potential of a given polarity, and a control diode having one of its elements connected to said tap so as to be charged with the same polarity potential as said tap and having its other element charged with an opposite polarity potential of a predetermined threshold-establishing value.

8. In an electrical control system, a vacuum tube having a pair of diodes, individual energizing circuits for rendering said diodes conductive selectively, a resistance capacity filter system associated with each of said diodes, an output circuit from one of said filter systems, and means inter-connecting said filter systems whereby said output circuit is charged with a negative potential when one of said diodes is conductive and is charged with a positive potential when the other of said diodes is conductive.

9. An electrical control system as defined in claim 8 wherein a first governing diode has its plate connected to said output circuit and its cathode charged to a predetermined positive threshold establishing potential, and a second governing diode has its cathode connected to said output circuit and its plate charged to a predetermined negative threshold-establishing potential.

10. In an amplifying transmission system, the combination of intensity controlled expander means operable to increase the gain in the system in response to sound energy in the system,

and means operable to limit such expansion to a predetermined level.

11. In a transmission system having grid-controlled electronic amplifying means, the combination of control means operable to produce a control potential in response to and varying in proportion to sound energy impressed on said amplifying means, a grid to which said control potential is applied, and means operable to limit the effective intensity of said control potential on 10 said grid to a predetermined level.

12. In a two-way loudspeaking communication system of the automatic or constantly active type and providing two communication channels each including transmitter means and loud speaker 15 reproducing means, both of said channels terminating in remotely located stations each of which includes the transmitting means of one of said channels and the reproducing means of the other of said channels, one of said means of each 20 station comprising two individual transducing devices connected in series to their channel and spaced apart a distance equal to one-half wave length of the natural period of the system.

13. In a two-way loud speaking communication 25 system of the automatic or constantly active type and providing two communication channels each including transmitter means and loud speaker reproducing means, both of said channels terminating in remotely located stations each of 30 which includes the transmitting means of one of said channels and the reproducing means of the other of said channels, the transmitting means of each station comprising two individual transmitters connected in series and spaced apart a distance equal to one-half wave length of the natural 35 period of the system.

14. In a two-way loudspeaking communication system of the automatic or constantly active type and providing two communication channels each including transmitter means and loud speaker 40 reproducing means, both of said channels terminating in remotely located stations each of which includes the transmitting means of one of said channels and the reproducing means of the other 45 of said channels, the reproducing means of each station comprising two individual reproducers connected in series and spaced apart a distance equal to one-half wave length of the natural period of the system.

15. In a two-way loud speaking communication system of the automatic or constantly active type and providing two communication channels each including transmitter means and loud speaker reproducing means, both of said channels terminating in remotely located stations each of which includes the transmitting means of one of said channels and the reproducing means of the other of said channels, the transmitter means of each of said stations including a single microphone 60 which is subjected to the sound reproduced by the reproducer of its station and travelling from the reproducer to the microphone along a direct path, and planar sound reflecting means operable to reflect such reproduced sound to said microphone 65 by the most direct path.

HAROLD J. McCREARY.
